[57] CLAIM

The ornamental design for a pulse generating machine
for use in treating tools, as shown and described.

DESCRIPTION

FIG. 1 is a perspective view of a pulse generating machine
for use in treating tools showing our new design;

FIG. 2 is a rear elevational view;

FIG. 3 is an end elevational view taken from the left in
FIG. 2;

FIG. 4 is a front elevational view;

FIG. 5 is an end view taken from the left in FIG. 4; and
FIG. 6 is a top plan view thereof.

The undisclosed bottom surface of the pulse generating
machine for use in treating tools is conventional in ap-
pearance.
